UNITED STATES PATENT OFFICE.

SAMUEL KELLETT, OF SAN FRANCISCO, CALIFORNIA.

DESIGN FOR CENTER-PIECE.

Specification forming part of Design No. 7,363, dated April 7, 1874; application filed March 16, 1874.
 [Term of Patent 14 years.]

To all whom it may concern:

Be it known that I, SAMUEL KELLETT, of the city and county of San Francisco, State of California, have invented and produced a new and original Design for a Center - Piece in Basso-Relievo, reference being had to the accompanying photograph and to letters marked thereon.

My new design consists of a drop or pendant, A, engraved and beaded on its base, as shown, extending from the base of the drop to the molding, and a plain leaf figure, B, with a stem and ball, C, alternating. Around this central form are placed four panel figures. The design consists of a shield, D, scroll E, rosette F, and terminal G, running right and

left, and finishing to a small device, H, crossing the panel. The outer border is composed of two forms, I and J, connected by a plain fillet.

Having thus described my invention, what I claim, and desire to secure by Letters Patent, is—

1. The inside form A, B, C, and D, as described.
2. The panel-work E, F, G, and H and outer border I and J, as described.

SAML. KELLETT.
